ABSTRACT OF THE DISCLOSURE

Apparatus adapted to be mounted in a stall shower for use in bathing the back of any user.

SUMMARY OF THE INVENTION

My apparatus includes a hollow container having spaced apart front and rear surfaces joined by side surfaces. Means connected to the rear surface detachably secures same to an interior wall of the shower. Means secured to one of the side surfaces introduces water into the container. The front surface is flexible and resilient, for example being formed of rubber with a corrugated surface having alternately spaced horizontally extending lands and valleys, which is perforated whereby water is expelled therethrough.

In use, the user first applies soap to the front surface and then moves his back into contact with this surface; by moving his back with an up and down movement with the water flow initiated, the back is automatically cleaned.

BRIEF DESCRIPTION OF THE DRAWINGS

In the drawings:

- FIG. 1 is a perspective view of my invention in use;
- FIG. 2 is a front view of my invention;
- FIG. 3 is a cross sectional view of my invention;
- FIG. 4 is a detail view of one part of my invention;
- FIG. 5 is a detail partially cut away front perspective view of my invention; and

FIG. 6 is a detail partially cut away rear perspective view of my invention.

DETAILED DESCRIPTION OF PREFERRED EMBODIMENTS

Referring now to FIGS. 1-6, a pair of oppositely disposed parallel vertical channel members 10 secured to a wall 12 of a stall shower engage corresponding side walls 14 of a hollow container having a flat rear wall 16 and a spaced apart front wall 18. Thumb screws 20 hold the side walls in the channel. Alternatively, the walls 14 can have extensions which are narrow and extend at right angles for connection in a channel.

The container has a front wall 18 which is corrugated with horizontal parallel lands 24 and valleys 26 and is

2

perforated as shown at 28. Wall 18 is covered by a flexible resilient layer 30 of sponge rubber and the like. A water feed line 32 is connected via a shut off valve (not shown) to any of side surfaces or walls of the container to introduce water therein which is then expelled through the perforations 28.

In use, the container is adjusted to the proper height, layer 30 is soaped, the water is turned on, and the user is able to obtain a complete and thorough back wash by moving his back up and down against the soaped continuously wet front surface of the container.

If desired, the channels can be replaced by rear mounted suction cups on rear wall 16.

While I have described my invention with particular reference to the drawings, my protection is to be limited only by the terms of the claims which follow.

Having thus described my invention, I claim as new and desire to secure by Letters Patent:

1. Apparatus adapted to be installed in a stall shower to be used to bathe the back of a user, said apparatus comprising a hollow container having spaced apart front and rear surfaces and side surfaces, means to detachably secure said rear surfaces to a wall of said shower, means connected to one of said side surfaces to introduce water into said container, said front surface being flexible and resilient and having perforations through which water is expelled.
2. Apparatus as set forth in claim 1 wherein said securing means includes a plurality of spaced apart suction cups.
3. Apparatus as set forth in claim 1 wherein said connected means is a hollow pipe.
4. Apparatus as set forth in claim 1 wherein said front surface is corrugated with alternatively spaced horizontally extending lands and valleys.
5. Apparatus as set forth in claim 1 wherein said securing means includes a pair of channels and guides for said channels.
